(57) **CLAIM**

The ornamental design for printer, as shown and described.

DESCRIPTION

FIG. 1 is a perspective view of a printer;

FIG. 2 is a front view thereof;

FIG. 3 is a top view thereof;

FIG. 4 is a perspective view thereof similar to FIG. 1, with a cover of a manual paper feeding portion in open positions;

FIG. 5 is another perspective view of FIG. 4;

FIG. 6 is perspective view of another embodiment of a printer, with a cover of a manual paper feeding portion in open positions; and,

FIG. 7 is another perspective view of FIG. 6.

The broken lines are for illustrative purposes only and form no part of the claimed design.

1 Claim, 4 Drawing Sheets

FIG. 1

FIG. 2

FIG. 3
